DESIGN FOR A WAIST

Marie Mascitelli, New York, N. Y.

Application October 11, 1938, Serial No. 80,373

Term of patent 3½ years

To all whom it may concern:

Be it known that I, Marie Mascitelli, a citizen of the United States of America, residing in New York city, in the Borough of Manhattan, county and State of New York, have invented a new, original, and ornamental Design for a Waist, of which the following is a specification, reference being had to the accompanying drawing, forming part thereof, wherein

I claim:

The ornamental design for a waist, substantially as shown.

MARIE MASCITELLI.
